Patented Oct. 24, 1922.

Inventor:

George M. Merrick
By Chas. E. Lord
Atty.

UNITED STATES PATENT OFFICE.

GEORGE M. MERWIN, OF BURWYN, ILLINOIS, ASSIGNOR TO INTERNATIONAL HARVESTER COMPANY, A CORPORATION OF NEW JERSEY.

SNAPPING ROLL.

Application filed August 29, 1919. Serial No. 320,726.

To all whom it may concern:

Be it known that I, GEORGE M. MERWIN, a citizen of the United States, residing at Burwyn, in the county of Cook and State of Illinois, have invented certain new and useful Improvements in Snapping Rolls, of which the following is a full, clear, and exact specification.

This invention relates to snapping rolls, 10 and more particularly to snapping rolls for corn handling machines, such as corn huskers and shredders.

It is common in machines of this character to utilize rolls for feeding the material 15 and for snapping ears from the stalks. It has been found desirable, however, to feed a portion of the ears with the stalks in order that these ears may be cut or shredded with the remainder of the stalk. The present invention has for its object, therefore, to feed 20 a plurality of corn stalks longitudinally and to snap from the stalks a portion of the ears and to have this action the entire width of the feed roll, but to retain certain other 25 ears and to feed them with the stalks.

In the present instance this invention is carried out by means of a snapping roll, or 30 if desired, a plurality of snapping rolls having longitudinal corrugations or ribs, certain portions of the corrugations being 35 cut away to provide longitudinal recesses. In feeding the stalks by means of such a roll, the recessed portions will permit certain of the ears to be fed, while the remainder of the ears will be snapped off.

I have illustrated in the accompanying drawings certain embodiments of my invention, and in these drawings—

Fig. 1 is a front elevational view illustrating my improved construction;

Fig. 2 is an enlarged detail view illustrating the end portions of two coating snapping rolls; and

Fig. 3, shown partly in section, is an end view of the construction shown in Fig. 2.

In the embodiment of the invention illustrated, I have shown a pair of snapping rolls, one of these rolls having the longitudinal recess above described, and the other 50 roll having longitudinal corrugations or ribs extending throughout its length.

In Fig. 1 a roll 10 is illustrated, this roll being provided with a plurality of longi-

tudinal ribs or corrugations, three of these ribs being illustrated and indicated by the 55 reference characters 11, 12 and 13. It will be seen that each of these longitudinal ribs is cut away for a third of its length, the rib 11 having its left hand third cut away, as shown at 14, the rib 12 having its central 60 third cut away, as shown at 15, and the rib 13 being cut away at its left hand, as shown at 16. The other snapping roll 17 is provided with a plurality of longitudinal ribs or corrugations 18, these ribs being 65 separated by longitudinal grooves 19. A plurality of bridge portions 20 is provided to bridge portions of the grooves, thereby increasing the feeding surface of the roll. If desired, however, the roll 17 may be made 70 with the usual longitudinal ribs and grooves, or in other words, may be longitudinally corrugated.

Having described the structure of my improved snapping roll, I will now briefly set 75 forth the operation of same.

As the corn stalks are fed between the rolls 10 and 17 it will be seen that the portion of the stalks disposed in the cutaway portion 16 will be allowed to retain their 80 ears, the ears being fed forward with the stalks. After the roll 10 has rotated for a portion of its revolution, the intermediate recessed portion 15 will allow certain ears to be fed and subsequently certain of the 85 ears will be fed through the recess 14. By arranging the recessed portion in the manner shown and described, I have provided a construction which will not interfere with the feeding of the stalks, but will permit 90 certain of the ears to be fed with the stalks.

While I have in the above specification described one embodiment of my invention, it will be understood that the invention is capable of modification, and that modifications and changes in the construction and arrangement of the parts may be made 95 without departing from the spirit and scope of the invention, as expressed in the following claims:

1. A snapping roll having a series of longitudinal ribs disposed around its cylindrical surface, each of said ribs having a single cut away portion for a portion of its length, the cut away portion on successive 105 ribs being disposed in staggered relation so

that the remaining portion of certain of said ribs aligns with the cut away portion and a remaining portion of an adjacent rib.

2. A snapping roll having a series of 5 longitudinal ribs formed on its surface, each of said ribs having a single cut away portion for a portion of its length,

certain of said ribs having the cut away portion positioned adjacent the ends of said roll and certain other of said ribs having 10 the cut away portion positioned centrally with respect to the ends of said roll.

In testimony whereof I affix my signature.

GEORGE M. MERWIN.
